UNITED STATES PATENT OFFICE.

LOUIS S. LOCKWOOD, OF NORTH TONAWANDA, NEW YORK, ASSIGNOR TO THE RUDOLPH WURLITZER MANUFACTURING COMPANY, OF NORTH TONAWANDA, NEW YORK, A CORPORATION OF NEW YORK.

DRUM.

Application filed May 20, 1924. Serial No. 714,588.

In orchestral organs and particularly those of motion picture theatres, practically all of the instruments of a full orchestra are represented, excepting the tympani or kettle drums. The use of ordinary drums of this type is impractical in such organs on account of their sensitiveness to climatic and atmospheric changes which renders it necessary to adjust them frequently in order

10 to keep them in tune.

The object of my invention is the provision of a drum which while accurately imitating the tone or timbre of the kettle drum, is practically unaffected by atmospheric changes and reliably retains its pitch when once tuned, thus especially adapting it for use in orchestral organs.

Another object is the production of a drum of this character which can be manufactured at much less cost than an ordinary kettle drum.

In the accompanying drawings: Fig. 1 is a side elevation of the improved drum associated with automatic means for beating it. Fig. 2 is a face view of the drum on an enlarged scale. Fig. 3 is a transverse section thereof, on line 3—3, Fig. 2. Fig. 4 is a similar section, on line 4—4, Fig. 2.

Similar characters of reference refer to 30 like parts throughout the several views.

This invention is based upon the discovery that a comparatively thin metallic drum head provided with suitable stiffening members, such as corrugations, produces

35 a quality of tone peculiar to kettle drums.

In the example of the invention illustrated in the drawings, the hollow body 10 of the drum is cylindrical and preferably provided at both ends with such metallic heads

40 11. Each head consists of a relatively thin plate of suitable sheet metal such as galvanized iron, having means for giving it the required resonance when beaten with the customary drum sticks 12. These resonance-devices may consist of stiffening or

45 re-enforcing ribs or corrugations 13 which are preferably arranged concentrically, as shown in the drawings, but which may be disposed radially or in any other suitable manner.

50 In its center each drum-head may be formed with a boss or convex portion 14 adapted to be struck by the drum-

sticks. This boss withstands the percussion effect and increases the resonance of the drum-head.

In the preferred construction shown, each metallic head is secured by screws 15 or other means to a wooden carrying ring 16 fitted in the adjacent end of the drum-body and fastened therein, for instance, by screws 17.

To prevent rattling of the drum heads, it is desirable to keep them out of contact with their carrying rings 16 and the drum-body 10 and for this purpose, packing strips 18 of leather or other appropriate material may be interposed between these parts and the heads, as shown in Fig. 3. These packings also form sealed joints between said parts.

This improved drum accurately and faithfully reproduces the timbre of the kettle drum. It affords the important advantage over the old drum of being unaffected by meteorological changes and therefore retains its pitch, avoiding the labor and annoyance of frequently adjusting and tuning the drum and rendering its use especially desirable in orchestral organs. Moreover, its cost is exceedingly small compared with that of kettle drums, effecting a material saving.

When used in an orchestrion or orchestral organ, the drum-sticks may be operated by a suitable pneumatic action, including motor pneumatics 19.

Any suitable means may be employed for tuning the drum. The devices shown in the drawings for this purpose, consist of a number of studs or bolts 20 secured to the outer side of the drum-head adjacent to the impact-boss 14 and each carrying one or more weights in the form of nuts 21. By applying a greater or less number of nuts to these bolts, the vibrations of the drum-head are reduced or increased and the pitch of the drum is lowered or raised accordingly.

I claim as my invention:

1. A drum of the character described, comprising a body and a percussive metallic head applied to the end of said body and having concentric corrugations.

2. A drum of the character described, comprising a body and a percussive me-

talic head applied to the end of said body and having a convex impact portion and corrugations arranged symmetrically between said convex portion and the margin of the head.

3. A drum of the character described, comprising a body and a percussive me-

talic head applied to the end of said body and having a central convex impact portion and concentric corrugations surrounding said convex portion.

Buffalo, N. Y., May 13th, 1924.

LOUIS S. LOCKWOOD.
